US00D689366S

(12) **United States Design Patent**
Kohne et al.

(10) **Patent No.:** **US D689,366 S**
(b4) **Date of Patent:** **** Sep. 10, 2013**

(54) **COSMETIC PACKAGE**

(75) Inventors: **Anna Kathryn Kohne**, Baltimore, MD (US); **Carolina Lavin**, Jersey City, NJ (US)

(73) Assignee: **The Procter & Gamble Company**, Cincinnati, OH (US)

(**) Term: **14 Years**

(21) Appl. No.: **29/368,208**

(22) Filed: **Aug. 20, 2010**

(51) LOC (9) Cl. **09-01**

(52) U.S. Cl.

USPC **D9/504; D9/552**

(58) **Field of Classification Search**

(57) **CLAIM**

The ornamental design for a cosmetic package, as shown and described.

DESCRIPTION

FIG. 1 is a perspective front view of the cosmetic package embodying our new design;

FIG. 2 is a front view thereof;

FIG. 3 bottom view thereof; and,

FIG. 4 is a top view thereof.

The appearance within the bottom end profile shown in FIG. 3 forms no part of the claimed design.

The figures are lined for gray, silver, violet, or purple in accordance with MPEP § 608.02.

1 Claim, 3 Drawing Sheets
